CLAIM

The ornamental design for a game housing, as shown and described.

DESCRIPTION

1. Game housing

Fig. 1.1 is a top perspective view of the game housing in accordance with the present design wherein the game piece components are in a first position;

Fig. 1.2 is a top perspective view thereof, wherein the game piece components are in another position;

Fig. 1.3 is a top perspective view thereof, wherein the game piece components are in yet another position;

Fig. 1.4 is a top plan view of the game housing;

Fig. 1.5 is a top perspective view of the game housing, shown without the game piece components for clarity;

Fig. 1.6 is another top perspective view thereof;

Fig. 1.7 is a right side elevation view thereof;

Fig. 1.8 is a left side elevation view thereof;

Fig. 1.9 is a front elevation view thereof;

(Continued)

Fig. 1.10 is a back elevation view thereof;
 Fig. 1.11 is a top plan view thereof; and
 Fig. 1.12 is a bottom view thereof.
